UNITED STATES PATENT OFFICE.

EDGAR E. GREVE, OF BELLEVUE, PENNSYLVANIA.

ROTARY DRILLING-MACHINE.

1,371,478.

Specification of Letters Patent. Patented Mar. 15, 1921.

Application filed August 20, 1919. Serial No. 318,653.

To all whom it may concern:

Be it known that I, EDGAR E. GREVE, a citizen of the United States, residing at Bellevue, in the county of Allegheny and State of Pennsylvania, have invented certain new and useful Improvements in Rotary Drilling-Machines, of which the following is a specification.

My invention relates to improvements in hydraulic drilling machines, particularly designed for use in drilling wells. Machines of the class to which my invention relates include a rotatable centrally apertured table, means for rotating the table, a drive-ring mounted on and connected with the table, one or more bushings co-acting with the drive-ring, a sectional drill stem, and a grip or grief stem connecting the drill-stem and the rotary table through the bushing or bushings. These parts are arranged so that the grip or grief stem is allowed a longitudinal movement through the bushings during the operation of drilling and are of such a character as to permit the grip stem and the sectional drill-stem to be lowered and raised through the rotary.

Owing to the fact that the drill-stem is made up of sections secured together by threaded couplings and the necessity for adding new sections as the well deepens, it will be understood that considerable time and labor are required in connecting and disconnecting the grip stem and the various sections composing the drill-stem.

So far as I am aware, rotary machines of the character to which the present invention relates, as heretofore constructed, have been incapable of being utilized for joining or connecting the various sections.

One of the principal objects of the present invention is to provide a rotary drilling machine of simple and efficient construction that may be utilized for joining the sections together as well as disconnecting the sections.

Other objects of the present invention are, to provide means for connecting and disconnecting pipe sections without rotating the sections in the hole below the rotary; new and improved bearings and lubricating means; means for preventing the rotary table from being accidentally raised from the bed-plate; means for preventing the entrance of mud, etc., to the movable parts of

the machine; means for connecting and disconnecting the drive-ring and rotary table.

In the accompanying drawings, which illustrate an application of my invention,

Figure 1 is a part elevational view and a part sectional view of a machine embodying my invention, the section being taken on the line 1—1 of Fig. 2; and

Fig. 2, a top plan.

Fig. 3 is a plan view of sectional slips which I employ.

Referring to the drawings, 2—2 designate suitable skids or supports for the bed plate or base 3, and 4 is a rotary table, the latter being provided with an annular rack 5 adapted to coöperate with drive-pinion 6 carried on drive-shaft 7.

The table, as illustrated and as preferred, has a central opening 8 into which the drive-ring is entered, said table being also provided with an annular depending portion 9 which extends downwardly through an opening in the base 3. The lower end of depending portion 9 is threaded as shown at 10 to engage a thrust ring 11, said thrust ring adapted to engage the under surface of the base 3, thereby preventing the table from working up through the base. Table 4 is designed to revolve on a series of roller bearings 12, the latter being located in an annular raceway 13 formed in the base 3.

14 designates a drive-ring adapted to be positioned on the table and designed to be connected to and disconnected therefrom by means of a horizontally movable pin or plug element 15. Drive-ring 14 is mounted on 90 bearings 16, the latter being disposed in a raceway 17 formed in the table.

The drive-ring 14, is formed with an interior tapered face 18, said tapered face or portion being designed to receive slips, the latter being designed to make engagement with the drill pipe for the purpose of suspending the pipe when desired. The drive-ring bushing 14 is also provided with an annular lower end formed with openings 20. The purpose of said openings 20 is to receive a sliding bolt 21, the latter being mounted and operative in a casing 22 secured to the underside of the base 3 by means of bolts 23. Sliding bolt 21 is moved 105 by means of a handle 24, and casing 22 is provided with two recessed portions 25 and 26, the latter being adapted to receive and

maintain the handle and the bolt 21 in operative and inoperative positions with respect to the lower end of the drive ring so as to prevent rotation of said ring relatively 5 to the table, or to permit rotation as desired.

Located in the drive-ring 14 I have shown two bushings 27 and 28, the outer bushing 27 being designed during normal drilling operations to be connected with the table and 10 with the drive-ring by means of the horizontally movable elements 15 and the bushing 28 to bushing 27 by a key 29. Connecting elements 15 are entered in alined openings formed respectively in the table, drive-ring and bushing 27 (see left of Fig. 1), said elements being actuated by a pin 30 having its lower end adapted to be entered in recesses 31 and 32. The position of these 15 parts in Fig. 1 shows the drive-ring and said bushing connected with the table and designed to rotate therewith, if the locking member 21 is withdrawn from an opening 20 of the drive-ring 14.

Drive-ring 14 is provided with a slightly 25 overlapping portion 33 designed to prevent mud, sand, etc., from working into the bearings, and the table 4 is also formed with a somewhat similar portion 34 to prevent foreign matter reaching the bearings 12.

30 The bearings 12 and 16 are lubricated from an oil reservoir formed in the drive-ring, said reservoir communicating with said bearings by means of passages 36 and 37. 38 designates roller thrust bearings interposed between the bed 3 and the annular 35 depending portion 9 of the table.

The table is provided with sockets or 40 recesses 39 designed to receive a post 40 known in this art as a break out post, and the drive-ring 14 is provided with similar 45 sockets 41 also designed to receive break-out posts. The function of the post 40 is to engage pipe tongs, not shown, designed to be secured to a section of the drill-stem or to the grip stem above the rotary table, thus 50 turning the section above the table by rotating the table.

In the operation of my machine the turning 55 of the section or sections above the table either for the purpose of connecting the sections or for disconnecting the sections is effected without turning the sections below the table.

During the drilling operations the drive-ring and bushings are designed to be driven 60 by the rotary table, the connecting elements 15 being in the position shown by Fig. 1 and the element 21 being withdrawn from contact with the lower end of the drive-ring.

Assuming the sectional drill stem and the 65 grip or grip stem connecting the drill stem with the rotary are in position for drilling and it is desired to disconnect the sections, the key 29 is removed, the string together with the grip stem is raised in the usual

well known manner, the coupling connecting the lower end of the grief and the upper section of the drill stem, or an element on the grief stem, coming into contact with the lower face of the bushings 28, raises the 70 bushings free of the drive-ring, thereupon slips are introduced for the purpose of sustaining the sections remaining in the hole below the rotary. I prefer to employ a set of three slips, as shown in Fig 3, said slips being tapered to coact with the tapered interior face of the bushings 27 and one of the slips *a* being provided with a lug *b* on back to enter a recess 42 of the said bushing 27, the slip *a* with the lug being formed with 75 vertical serrations and the other slips *c* with horizontal serrations. Slips of the character described are shown in U. S. Patent No. 1,259,855 of March 19, 1918. After the slips are positioned locking element 15 is moved 80 by its pin 31 from the position shown by Fig. 1, inwardly, thus carrying said element free of the table 4. For the purpose of preventing the rotation of the drive-ring, element 21 is moved into the dotted line 85 position shown in Fig. 1.

A break-out post or posts are then placed in position to contact with tongs placed on a section above the rotary and the table together with said post or posts revolved in the desired direction to disconnect a section above the rotary with the sections or section below the rotary by rotating the section or sections above rotary and at the same time preventing the lower section or sections from 100 turning.

It will be evident that the sections may be connected together in substantially the manner described by reversing the direction of rotation of the table.

It will be noted that the inner surface 18 of drive-ring 14 is tapered to coact with slips, and in case large pipe sections are employed bushing 27 may be omitted and a larger grip or grief stem engaging bushing, 110 as 28, may be employed.

What I claim is:

1. A rotary drilling machine comprising a base, a raceway in said base having bearings therein, a rotary table carried by said bearings, means for rotating the table, a raceway on said table having bearings therein, a drive-ring carried by the bearings, means operable for locking the drive-ring and table in driving relation, and means operable for holding the drive-ring against rotation when it is desired to rotate only the table.

2. A rotary drilling machine comprising a base, a race-way in said base having bearings therein, a rotary table carried by said 125 bearings, means for rotating the table, a race-way on said table having bearings therein, a drive-ring carried by the bearings, means operable for locking the drive-ring and table in driving relation, means operable for 130

holding the drive-ring against rotation when it is desired to rotate only the table, said drive-ring and table each having portions thereon for preventing the entrance of sand 5 and mud to the respective bearings.

3. A rotary drilling machine comprising a base having a central opening, anti-friction rollers carried by said base, a table having a depending portion extending into the opening and rotatably mounted on said rollers, means for rotating the table, anti-friction rollers carried by the table, a drive-ring mounted on the rollers, means for locking the drive-ring in driving relation with the 10 table, means operable for locking the drive-ring against rotation when it is desired to rotate only the table, and a thrust member secured to the depending portion of said table and adapted to engage the said base 15 whereby vertical movement of the table relative to the base is prevented.

4. A rotary drilling machine comprising a base portion having an annular race-way thereon provided with bearings, a rotary 20 table carried by the base portion and supported by the bearings, a race-way having bearings therein on said table, a drive-ring supported on the bearings in the table, an oil reservoir in the drive-ring, passages for 25 conducting oil from the reservoir to the race-way, means for rotating the table, means for imparting the rotation of the table to the drive-ring, and means for holding the drive-ring against rotation when it is desired to 30 rotate only the table.

5. A rotary drilling machine comprising a stationary base portion, anti-friction bearings on the base portion, a rotary table mounted on the bearings, means for rotating 35 the table, anti-friction bearings carried by the table, a drive-ring supported on the anti-friction bearings in the table, said anti-friction bearings on the table permitting of the relative rotation between the drive-ring 40 and the table, means for locking the drive-ring and table against relative rotation whereby the drive-ring may be rotated with the table, and other means operable for holding said drive-ring against rotation when 45 said locking means is inoperative and it is desired to rotate only the table.

6. A rotary drilling machine comprising a stationary base, anti-friction bearings on the base portion, a rotary table mounted on the bearings, means for rotating the table, 55 anti-friction bearings carried by the table, a drive-ring supported by the anti-friction bearings on said table, said anti-friction bearings on the table permitting of relative rotation between the drive-ring and table, 60 said table and drive-ring being provided with openings adapted to be brought into alinement, means slidable in the openings for locking the drive-ring and table against relative rotation whereby the drive-ring may 65 be rotated with the table, and other means operable for holding said drive-ring against rotation when said locking means is inoperative and it is desired to rotate only the 70 table.

7. A rotary drilling machine comprising a base portion, anti-friction bearings on said base portion, a rotary table carried by said bearings, means for rotating the table, anti-friction bearings on the table, a drive-ring 75 carried by the said anti-friction bearings on the table, a removable bushing in said drive-ring, a second removable bushing in said first bushing, a locking means operable for engaging said rotary table, drive-ring and 80 first mentioned bushing when it is desired to rotate them in unison, said locking means being operable to disengage the first named bushing or the rotary table, and means on the base portion operable for engaging the 85 drive-ring and holding the drive-ring and its bushings against rotation when it is desired to rotate only the table.

8. In a rotary drilling machine, a rotary 90 table, means for rotating the table, a drive-ring, outer and inner bushings within the drive-ring, means for connecting and disconnecting the table drive-ring and outer bushing, and means for preventing a vertical movement of the inner bushing relatively to 95 the outer bushing.

In testimony whereof, I affix my signature in the presence of two witnesses.

EDGAR E. GREVE.
